UNITED STATES PATENT OFFICE

153,150

DESIGN FOR A HEARING AID CASING

Denison B. Hull, Winnetka, Ill., assignor to
Otarion, Inc., Chicago, Ill., a corporation of
Illinois

Application July 7, 1948, Serial No. 147,420

Term of patent 14 years

(Cl. D26—14)

To all whom it may concern:

Be it known that I, Denison B. Hull, a citizen of the United States residing at Winnetka, in the county of Cook and State of Illinois, have invented a new, original, and ornamental Design for a Hearing Aid Casing, of which the following is a specification, reference being had to the accompanying drawing, forming a part thereof.

In the drawing:

Fig. 1 is a front elevational view of the casing, illustrating my new design;

Fig. 2 is a view in side elevation of the casing;

Fig. 3 is a rear view of the casing; and

Fig. 4 is a top plan view of the casing.

The dominant features of the design reside in the portions shown in solid lines.

I claim:

The ornamental design for a hearing aid casing, substantially as shown and described.

DENISON B. HULL.
